[57] CLAIM

The ornamental design for a combined armrest and container holder, as shown and described.

DESCRIPTION

FIG. 1 is a perspective view of a combined armrest and container holder showing our new design;

FIG. 2 is a top plan view on an enlarged scale;

FIG. 3 is a bottom plan view on an enlarged scale;

FIG. 4 is a side elevational view on an enlarged scale,

the opposite side being a mirror image thereof;

FIG. 5 is a front elevational view on an enlarged scale; and

FIG. 6 is a rear elevational view on an enlarged scale thereof.

FIG. 1

FIG. 2

FIG. 3

FIG. 4

FIG. 5

FIG. 6
